UNITED STATES PATENT OFFICE.

JOHN A. WHERRY, OF NEW ORLEANS, LOUISIANA, ASSIGNOR TO UNDERWOOD TYPE-WRITER COMPANY, OF NEW YORK, N. Y., A CORPORATION OF DELAWARE.

SHEET-HOLDER FOR TYPE-WRITING MACHINES.

1,299,525.

Specification of Letters Patent.

Patented Apr. 8, 1919.

Application filed March 17, 1917. Serial No. 155,380.

To all whom it may concern:

Be it known that I, JOHN A. WHERRY, a citizen of the United States, residing in New Orleans, in the parish of Orleans and State 5 of Louisiana, have invented certain new and useful Improvements in Sheet-Holders for Type-Writing Machines, of which the following is a specification.

My invention relates to collating devices 10 for use in typewriting machines and is here- in disclosed as a flexible carrier adapted to have sheets placed and collated therein pre- paratory to insertion in the typewriting ma- chine, the carrier being so constructed that 15 it, together with the sheets, may be inserted into the typewriting machine.

In such devices, it is advantageous to pro- 20 vide means for holding sheets not only the full width of the collating sheets, but also sheets which extend only partly across the device, thus enabling a record sheet to be of one width, while the original or duplicate 25 may be of another width. The smaller sheet needs to be firmly held, and since it is held only on one side, to prevent twisting, the holding device must grip it securely at the side, and yet be of such a character that it 30 will pass around the platens of ordinary typewriting machines, these being machines in which the platen is revoluble and in which work-sheets are held against the platen by means of feed rolls.

I have found it possible to obtain a satis- 35 factory device of this character by making the carrier of a sheet of celluloid, or strong, fibered paper, such for example, as pure rope manilla, and turning over the edges of this sheet to form flaps for holding the work and record sheets. In order to enable these flaps 40 to securely hold the work-sheets and record sheets, I enable the flap to effectively co- operate with the body of the collating sheet by means of devices on the flap or sheet, or both. I find it advantageous to make these 45 devices take the form of eyes, *i. e.*, openings; said eyes advantageously being eyelets let into the sheet or flap, thus forming an opening into which the work-sheets and record sheets may be pinched by means of co- 50 operating projections, so placed on the sheet, as to face the center of the eyelet when the flap of the collating sheet is folded down flat. Thus each eyelet and its projection pinch the sheets lying between them and 55 hold them securely.

The eyelets or projections, or both, add to the grip which the flattened-down flap gets on the work and record sheet, so that the mere bending of the collating sheet, in passing it around the platen of the typewriter, 60 brings the flap against the body of the sheet with sufficient pressure to make the projections co-operate with the openings very effectively to hold the work and record sheets.

Other features and advantages will here-inafter appear.

In the accompanying drawings, Figure 1 is a perspective view of part of a typewriter carriage showing a collating 70 sheet passed around the platen thereof.

Fig. 2 is a view showing the collating sheet with assembled work and record sheets ready to have its flaps folded down.

Fig. 3 is a greatly enlarged section show- 75 ing how the gripping devices grip the rec- ord and work-sheets.

Fig. 4 is a section similar to Fig. 3, but showing a modification in which the boss is sharp and acts as an impaling pin.

The collating sheet 1, which may be of suitable ledger paper or rope manilla, is provided with longitudinal flaps 2 and 3, one being on each margin thereof, which are adapted to be folded down to overlie 85 a record sheet 4, which, by means of a car- bon sheet 5, receives the impress of matter written on the original 6. Other record sheets or duplicate originals 7 and 8 may be provided for special kinds of work, each 90 receiving its record by means of a carbon sheet 9. The collating sheet may also hold in place a record or tally sheet 10, which, unlike the sheets 4, 6, 7 and 8, extends only part way across the face 1, and has above 95 it and corresponding thereto in size a carbon sheet 11, so that items written in certain parts of a line will be imprinted on the narrower sheet 10, whereas, items written in other parts of a line, will not be so 100 imprinted.

The leading edge of the collating sheet is formed as a turned-over flap 12, the fold 13 of which may serve as an end gage for positioning one or more of the work-sheets. The side folds 14 also may serve as gages to aid in positioning work-sheets. In in- 105 serting the leading edge 12 into the machine it is folded down flat, and in order to pre- vent the device, including the assembled 110

work-sheets, from being very thick at the corners 15 of the leading edge, the side flaps 2 and 3 are cut away as seen at 16, so that they underlie only a part of the flap 12 when 5 that is folded down.

In order to enable the work and record sheets to be firmly gripped by the turned-down flaps 2 and 3, either the flap or the body of the collating sheet is provided with 10 a boss projection 17, shown herein as on the body of the collating sheet, which directly faces an opening 18 in the flap when the flap is folded down. Thus, when the collating sheet 1 has its flaps folded down, the 15 work-sheets which lie between the projection 17 and the opening 18, are firmly gripped at that point. The bosses 17, in the case of a paper body 1, are advantageously in the form of rivets, having a rather sharp 20 dome to engage the work-sheets.

In order to securely hold the work-sheets which may not lie against the folds 14, and, therefore, have not the benefit of said folds as a margin gage to assist in holding them 25 from turning, there is provided a series of these projections 17 and openings 18 for each of the flaps 2 and 3, so that any work-sheet, which is likely to be placed on the collating sheet 1, will be gripped by at least 30 two of each of the coöperating projections 17 and openings 18.

The gripping effect of the projections 17 and the openings 18 of course, is greatly enhanced by the bending of the collating 35 sheet 1, when it is passed around the platen 19 of the typewriter, because this bending which results from holding it against the platen by feed rolls 20 and guide rolls 21, makes the flaps bind firmly against the body 40 of the collating sheet.

The openings 18 are advantageously made by inserting eyelets 22 into the collating sheet, and these not only serve to protect the margins of the openings 18, but also increase 45 the gripping effect of the projections because the eyelets form a slight thickening of the collating sheet 1 itself. Both the eyelets 22 and projections 17 are placed some distance from the edge of the flap in its 50 folded down position. In order to make the collating sheet 1 feed evenly and smoothly around the typewriting machine, with whatever sheets it holds, the eyelets 22 and projections 17 are advantageously 55 placed, so that they lie between the usual feed rolls 20, which are spaced apart axially in most typewriting machines. Where the eyelets 22 and projections 17 are thus positioned, the feed rolls 20 get a firm grip on 60 the smooth surface of the collating sheet and its flaps, and thus feed it forward evenly and smoothly.

It will be found usually desirable in placing work-sheets in the machine, to have the 65 carbon sheets terminate under the flaps 2

and 3, but yet not extend so far under the flaps as to reach the projections 17, they being placed in the position best shown in Fig. 3. When thus positioned, the carbon sheets are not liable to cause any more smutting than they would if there were no holding devices for the work-sheets. It will be apparent, however, that by having the carbon sheets extend slightly under one or the other of the flaps 2 or 3, or both, they will 70 be more satisfactorily held in place between the work and record sheets. 75

Variations may be resorted to within the scope of the invention, and portions of the improvements may be used without others. 80

Having thus described by invention, I claim:

1. A collating sheet adapted to be inserted in a typewriter around a curved platen, said sheet comprising a flexible body portion and 85 a flexible side flap, one of said parts being provided with an opening, and the other with a boss so positioned as to register with said opening when said flap is in folded position, and coöperating therewith to form 90 means for attaching a work-sheet to said collating sheet by gripping a portion of the inserted margin of the work-sheet between said boss and the part of said collating sheet surrounding said opening. 95

2. A collating sheet comprising a body portion and a flap, one of said parts being provided with an opening, and the other with a boss so positioned as to register with said opening when said flap is in folded position, and coöperating therewith to form 100 means for attaching a work-sheet to said collating sheet by gripping a portion of the inserted margin of the work-sheet between said boss and the part of said collating sheet 105 surrounding said opening.

3. A collating sheet adapted to be inserted in a typewriter around a curved platen, said sheet comprising a flexible body portion and a flexible side flap, one of said parts being 110 provided with an opening, and the other with a boss so positioned as to register with said opening when said flap is in folded position, and coöperating therewith to form means for attaching a work-sheet to said collating sheet by gripping a portion of the inserted margin of the work-sheet between 115 said boss and the part of the collating sheet surrounding said opening, said collating sheet being provided with a thickened protecting marginal portion surrounding said opening and projecting slightly from the surface facing said boss, so as to enhance the gripping action. 120

4. A collating sheet adapted to be inserted 125 in a typewriter around a curved platen, said sheet comprising a flexible body portion and a flexible side flap, one of said parts being provided with a plurality of openings, and the other with a plurality of bosses so posi- 130

tioned as to register with said openings when said flap is in folded position, and co-operating therewith to form means for attaching a work-sheet to said collating sheet by gripping portions of the inserted margin of the work-sheet between said bosses and the parts of the collating sheet surrounding said openings.

5. A collating sheet adapted to be inserted in a typewriter around a curved platen, said sheet comprising a flexible body portion and a flexible side flap, one of said parts being provided with a plurality of openings, and the other with a plurality of 10 projecting elements so positioned as to register with said openings when said flap is in folded position, said projecting elements and their registering openings co-operating to form paper-fastening devices for attaching 15 a work-sheet to said collating sheet by engagement with parts of the work-sheet margin inserted between said body portion and said flap.

6. A collating sheet adapted to be inserted in a typewriter around a curved platen, said sheet comprising a flexible body portion and a pair of flexible flaps, one at each side thereof, each of said flaps and the adjacent part of said body portion being provided, 20 the one with a plurality of openings, and the other with a plurality of projecting elements so positioned as to register with said openings when said flaps are in folded position, said projecting elements and their 25 registering openings co-operating to form paper-fastening devices for attaching a work-sheet to said collating sheet by engagement with parts of the work-sheet margins inserted between said body portion and said 30 flaps.

7. A collating sheet adapted to be inserted in a typewriter around a curved platen, said sheet comprising a flexible body portion and a pair of flexible flaps, one at each 40 side of said body portion, each of said flaps and the adjacent part of said body portion being provided, the one with a plurality of openings, and the other with a plurality of 45 projecting elements so positioned as to register with said openings when said flaps are in folded position, said projecting elements and their registering openings co-operating to form paper-fastening devices for attaching a work-sheet to said collating sheet by engagement with parts of the work-sheet margins inserted between said body portion and said flaps, said collating sheet also comprising an end flap to overlie an edge of the 50 work-sheet and an end of each of said side flaps so as to form a means for guiding the work-sheet around the platen.

8. A collating sheet adapted to be inserted in a typewriter around a curved platen, said sheet comprising a flexible body portion 55 and a flexible side flap, one of said parts be-

ing provided with an opening, and the other with a projecting element so positioned as to register with said opening when said flap is in folded position, said projecting element and its registering opening co-operating to 70 form a paper-fastening device for attaching a work-sheet to said collating sheet by engagement with a part of the work-sheet margin inserted between said body portion and said flap, said collating sheet also comprising an end flap to overlie an edge of the work-sheet and one end of said side flap so as to form a means for guiding the work-sheet around the platen.

9. A collating sheet comprising a body 80 portion and a side flap, one of said parts being provided with an opening, and the other with a projecting element so positioned as to register with said opening when said flap is in folded position, said projecting element and its registering opening co-operating to 85 form a paper-fastening device for attaching a work-sheet to said collating sheet by engagement with a part of the work-sheet margin inserted between said body portion and said flap, said collating sheet also comprising an end flap to overlie an end of the work-sheet and one end of said side flap.

10. A collating sheet comprising a body 95 portion and a flap, one of said parts being provided with an opening, and the other with a projecting element so positioned as to register with said opening when said flap is in folded position, said projecting element and its registering opening co-operating to 100 form a paper-fastening device to engage the margin of a work-sheet when inserted between said body portion and said flap.

11. A collating sheet comprising a body portion and a flap, one of said parts being provided with a plurality of openings, and the other with a plurality of projecting elements so positioned as to register with said 110 openings when said flap is in folded position, said projecting elements and their registering openings co-operating to form paper-fastening devices to engage the margin of a work-sheet when inserted between said flap and said body portion.

12. A collating sheet comprising a body portion and a flap, one of said parts being provided with an opening, and the other with a boss so positioned as to register with 120 said opening when said flap is in folded position, and co-operating therewith to form means for attaching a work-sheet to said collating sheet by gripping a portion of the inserted margin of the work-sheet between 125 said boss and the part of the collating sheet surrounding said opening, said collating sheet being provided with a thickened protecting marginal portion surrounding said opening and projecting slightly from the 130

surface facing said boss, so as to enhance the gripping action.

13. A collating sheet adapted to be inserted in a typewriter around a curved 5 platen, said sheet comprising a flexible body portion and a flexible side flap, one of said parts being provided with an opening, and the other with a projecting element so positioned as to register with said opening 10 when said flap is in folded position, said

projecting element and its registering opening coöperating to form a paper-fastening device to engage the margin of a work-sheet when inserted between said flap and said body portion.

JOHN A. WHERRY.
